WARMER FOR CASUALTY EVACUATION
BAGSDonald M. Stadd, New York, N. Y., and Raymond
Paul Schreiber, Washington, D. C.

Application November 15, 1949, Serial No. 127,384

2 Claims. (Cl. 126—208)

1

The invention described herein, if patented, may be manufactured and used by or for the Government for governmental purposes without the payment to me of any royalty thereon.

This invention relates to warmers for casualty evacuation bags and sleeping bags and has for one of its objects to provide a catalytic warmer of compact construction which may be readily slipped into a casualty bag or sleeping bag and will furnish the required amount of heat without liability of injury to the occupant.

A further object of the invention resides in the provision of a warmer comprising three elements, namely, a fuel reservoir, a catalytic heater, and a sheath or envelope for the fuel reservoir and heater.

Another object of the invention consists in providing a sheath or envelope which is porous on one side and non-porous on the opposite side, and which is a functional part of the warmer in that it acts as a fixed temperature control and aids in more effective heat distribution.

Other objects and advantages of the invention will be apparent from the following description taken in connection with the accompanying drawings, in which

Fig. 1 is a perspective view of the catalytic warmer in its completed form ready for use;

Fig. 2 is a plan view of the warmer in opened position with a portion of the catalytic heating element curled back in order to disclose the fuel reservoir;

Fig. 3 is an end view of the fuel reservoir and pyrophoric igniter;

Fig. 4 is a longitudinal sectional view through the warmer in its folded position ready for use; and

Fig. 5 is an enlarged fragmentary sectional detail view of the fuel reservoir.

As heretofore mentioned, the warmer of the present invention is intended for use in association with a casualty evacuation bag or a sleeping bag. The warmer comprises three primary elements, namely, a shield or envelope indicated generally by the numeral 1 and composed of upper and lower hinged sections 2 and 3 respectively, a catalytic bed or heating element 4, and fuel reservoir 5.

The sections or halves 2 and 3 of the envelope 1 are hingedly connected by a flexible hinge 6, and the three edges may be releasably secured by a conventional zipper or slide fastener construction 7. It will be understood that each of these two sections of the envelope or shield is composed of a plurality of layers of insulation for properly in-

2

closing the catalytic heater and the fuel reservoir associated therewith. The upper half or section of the shield comprises an outer sheet of coarse woven fabric preferably of fiberglass, and indicated by the numeral 8. Just below the sheet 8 of fiberglass (Fig. 4) are two layers 9 of fiberglass insulation, although it will be readily understood that the number of layers may be increased or decreased as desired. Below the fiberglass layers 9 is a pair of sheets 10 of coarse woven fiberglass and below that is another layer 11 of fiberglass insulation. Below this last layer of fiberglass insulation is sheet 12 of coarse woven fiberglass. The edges of these various layers of fiberglass insulation and the inclosing and interposed sheets of coarse woven fiberglass may be united by stitching or the like 13 to provide a unitary construction.

The lower section 3 of the shield or envelope is similarly composed of a top layer 14 of coarse woven fiberglass, a plurality of layers 15 of fiberglass insulation, and an interposed layer 16 consisting of one or more sheets of aluminum or other metal foil, there being six of such sheets shown in the present illustration. These various layers forming the lower half or section 3 of the shield or envelope may also be united at their edges by stitching or the like 17 for providing a unitary construction.

The catalyst bed or heating unit may be composed of a plurality of layers of fiberglass insulation indicated generally by the numeral 18 and distributed on the interior of this fiberglass mass is a charge of palladium or platinum black spread as evenly as possible along the bed and indicated by the numeral 19. The layers of fiberglass insulation with the inclosed palladium black are completely wrapped in a sheet 20 of coarsely woven fiberglass which is doubled over the layers of insulation and has its three edges stitched together with wire staples or the like 21. This catalyst bed is provided with snap fasteners 22 in its four corners which are complementary to similar fasteners 23 secured to the four corners of the lower section 3 of the envelope or shield, thereby providing for releasably attaching the catalyst bed or heating element in cooperative relationship to the fuel reservoir 5.

This fuel reservoir is of shallow construction and preferably stamped out from sheet aluminum to provide a body portion 24 open at its top and closed by a cover 25 also formed of aluminum and permanently held in position by a series of rivets 26. Disposed between the closure 25 and a flange on the body portion 24 of the reservoir is a gasket

27 formed of neoprene or the like. Within the reservoir body 24 is a plurality of layers of fiber-glass batting insulation 28 which serves as a fuel absorbent and the top 25 is provided with a centrally disposed opening 29 across which extends a wire mesh screen 30 which serves to close the opening 29 against the exit of any of the fuel absorbent 28. The cover 25 may be provided with an extension 31 which extends beyond the body 24 of the reservoir and serves as a mounting for 10 pyrophoric lighter comprising a disk 32 of pyrophoric material pressed against a slidably mounted file-like igniter 33 by means of leaf springs 34 secured on the extension 31 by means of a rivet 35.

As clearly indicated in Fig. 4 the reservoir 5 is 15 mounted on the lower section 3 of the envelope and the catalyst bed is superimposed thereon and held in position by the complementary snap fasteners 22 and 23 just referred to, thereby releasably supporting the bed in its cooperative relation with the reservoir.

In use, the slide fastener 7 is operated to release the envelope 1 so that the sections 2 and 3 may be swung to open position as shown in Fig. 2. Thereafter the fuel reservoir 5 may be removed 20 and charged with fuel, such as gasoline or leaded gasoline, by pouring the same through the opening 29 to be absorbed by the fiberglass 28 within the reservoir. The operation of the heater may then be initiated by pouring a small amount (half an ounce or so) of fuel on the center of the heating element 4. If extra fuel is not available for starting the heating element, the reservoir may be inverted over the element 4 and pressed on either side of the opening 29 to cause the fuel to drip from the opening or transfer from reservoir to heating element by capillary action. The fuel on the element 4 may then be lighted by using a match or by inverting the reservoir 5 over element 4 and operating the pyrophoric igniter 32—33. The fuel reservoir is then slid between the heating element 4 and the lower section 3 of the envelope, with the open side in contact with the heating element. Thereafter the flame is allowed to burn out and the envelope is then closed and 45 the slide fastener operated to secure the envelope in closed position. The unit is then placed in the desired position in a casualty bag or sleeping bag with the top side, that is, the side exposed to the opening 29, directed away from the occupant of the bag.

By reason of the porous upper section of the envelope and the non-porous lower section, due to the position of the layers of metal foil and the metal reservoir, the heat generated in the warmer passes to the space within the bag and yet the occupant is protected from excessive direct heat if the warmer is positioned in the manner indicated above. Also it is to be noted that by reason of the non-porous underside in conjunction with the porous upperside a unit is provided in which the input of oxygen and the output of carbon

dioxide must travel slowly and through only one side of the unit, thus preventing a through draft and serving as a fixed temperature control.

To extinguish the burner it is only necessary 5 to operate the slide fastener so as to permit the removal of the fuel reservoir 5 which is thereafter placed on top of the heating element 4, and the slide fastener is then moved to closing position.

From the foregoing description and the attached drawings, it will be noted that we have devised a novel construction of warmer for casualty bags and the like, that the insulated heating element is detachably connected within the envelope and is therefore readily replaceable if and when the catalyst becomes poisoned, that the envelope is a functional part of the warmer in that it serves as a fixed temperature control and aids in more effective heat distribution, as well as insulating the warmer with respect to the body of the occupant; and that no variable temperature control is required since the warmer creates its own "ambient" temperature immediately surrounding itself within the casualty evacuation bag shortly after ignition.

25 We claim:

1. A warmer for casualty bags and the like comprising a catalytic heating element, said element including a bed of fibrous material and a catalyst disposed on the interior thereof, a fuel reservoir in contact with said bed and provided with an opening for the passage of fuel to the bed, and a porous insulating envelope inclosing the heating element and reservoir, said envelope comprising hingedly connected sections, and one or more layers of metal foil extending across one 30 of said sections.

2. A shield or envelope for a catalytic heater, comprising porous hingedly connected sections, each section comprising one or more layers of fiberglass insulation disposed between sheets of woven material, and one or more sheets of metal foil disposed in one of said sections and co-extensive with the area thereof.

DONALD M. STADD.
